UNITED STATES PATENT OFFICE.

HORACE E. CHADWICK AND HORACE P. LESTER, OF PROVIDENCE, R. I.

DESIGN FOR A BRACELET.

SPECIFICATION forming part of Design No. 14,391, dated November 6, 1883.

Application filed July 30, 1883. Term of patent 3½ years.

To all whom it may concern:

Be it known that we, HORACE E. CHADWICK and HORACE P. LESTER, citizens of the United States, residing at Providence, in the county 5 of Providence and State of Rhode Island, have invented and produced a new and original Design for Bracelets, of which the following is a specification, reference being had to the accompanying drawings, forming part thereof.

10 Figure 1 is an edge or side view of our improved bracelet. Fig. 2 is a top view.

Our design consists of a series of alternately engraved and plain cylindrical rods, having upon each end an ornamental cap, presenting 15 an appearance of being connected transversely, as shown.

In the accompanying drawings, A, Figs. 1 and 2, is a bracelet composed of a series of cylindrical rods, *a a* and *b b*, which are cut to

a suitable and uniform length, and arranged 20 parallel with each other. Upon each end of each rod is a cap, *c c*, making a finish to and ornamenting the same. To the top of the bracelet is attached a disk or plate of metal, B, which is ornamented with a monogram or 25 stone, as shown.

What we claim, and desire to secure by Letters Patent, is—

The design for bracelet, herein shown and described, consisting of a series of cylindrical 30 rods alternately engraved, and having upon each end a cap, presenting an appearance of being connected transversely, as shown.

HORACE E. CHADWICK.

HORACE P. LESTER.
